UNITED STATES PATENT OFFICE.

WILLIAM H. GOODDAY AND LOUIS F. GEMEINER, OF NEW YORK, N. Y.

APPARATUS FOR TREATING CLOTHS AND OTHER GOODS TO RENDER THEM MOTH OR VERMIN PROOF OR REPELLENT.

SPECIFICATION forming part of Letters Patent No. 248,306, dated October 18, 1881.

Application filed August 30, 1881. (No model.)

To all whom it may concern:

Be it known that we, WILLIAM H. GOODDAY and LOUIS F. GEMEINER, both of the city, county, and State of New York, have invented 5 a new and useful Improvement in an Apparatus for Treating Cloths and other Goods to Render them Moth or Vermin Proof or Repellent, of which the following is a specification.

This invention consists of a series of concentric cylinders having perforated sides and closed ends, into one of which ends a steam-pipe is introduced for conducting steam into the innermost of the cylindrical chambers, so as to allow the said steam to pass outwardly 15 through the perforations of the sides of the said inner cylinder, and thence through the annular chamber surrounding the said inner cylinder, and between it and the intermediate cylinder, and the steam will then enter an annular chamber between the outer shell and the 20 inclosed chambers, from which said annular chamber the steam will be expelled outwardly through the perforated sides of the outer cylinder and saturate the cloth or other goods that 25 are to be treated, the said goods to be treated having been wrapped or wound around the outer cylinder, so as to be immediately accessible to the steam. The steam, in passing through the first annular chamber surrounding the inner steam-chamber, will be charged with some 30 subtle pungent material that will prove destructive to any moth or similar insect life.

The invention will be readily understood by reference to the accompanying drawings, of 35 which—

Figure 1 is a longitudinal sectional elevation of the improved apparatus. Fig. 2 is a transverse sectional elevation of the same. Fig. 3 is a side elevation of it.

40 The machine or apparatus consists of three concentric cylinders, A, B, and C, the ends of which terminate in nearly the same vertical plane, and the said three concentric cylinders form two concentric annular chambers, D and E.

45 The front end, a, may be formed of one single plate, which will constitute the ends of all of the cylinders; or each cylinder may have an end independent of the others. At the other end of the cylinders there will be an 50 outside end plate, G, which will form the end

for the two outer cylinders, B and C, and an inside end, which will form the end for the inner cylinder. The end plate, G, will be secured steam-tightly to the cylinder C by any suitable means, and there will be two end trunnions, H and I, secured, respectively, to the end plates, a and G, in the prolongation of the axial line of the cylinders, so that these trunnions may be set in suitable rests, in order that the cylinders may be rotated on these trunnions or 55 gudgeons for the purpose of winding the cloth or other goods to be treated upon or around the outer cylinder or unwinding the goods therefrom. The trunnion or gudgeon I will be hollow, so as to admit steam to the inner cylinder, A, with which this hollow journal is to be connected. The outer end of the journal I is to be made so that it may be coupled onto a steam-pipe for filling these chambers with steam when required.

60 All of the cylinders A, B, and C will have perforated sides, so as to allow the steam with which the inner chamber is charged to percolate outward through the sides of each of the said chambers in succession.

70 The inner annular chamber, D, is to be filled with some suitable pungent moth or vermin repelling material, which may be taken up and carried along with the steam, and discharged thereby into the goods surrounding the outer cylinder. For this purpose we prefer to use 75 quassia-wood, sawdust, or chips, though chips or fragments of either calamus root, Eugenia, or coloquintida may answer the purpose. If either of these materials are filled into the chamber 80 D, the steam from the interior chamber, A, will pass outwardly through the perforated sides of the said inner cylinder and through the medicating-chamber D, where the steam will take up a sufficient quantity of the medicating 85 material to impregnate or saturate the goods wound about the outer cylinder to such an extent as to destroy or repel any moths or other similar vermin.

90 In order to be certain that none of the perforations of the outer cylinder are stopped or clogged by the medicating material, thereby causing irregularities or untreated spots in the goods, we interpose between the outer cylinder and the medicating-chamber an annular chamber 95 100

ber, E, which is simply a steam-chamber, where the medicated steam will become thoroughly mixed and homogeneous. From this steam-chamber E the medicated steam will pass out through the perforations of the outer chamber, and thence thoroughly permeate and treat the surrounding goods, so as to thoroughly repel moths or other similar vermin therefrom.

It is desirable to place the cylinders in a horizontal position when the goods are to be wound around them; but it will be better to place the said cylinders in a vertical position when the steam is turned on, so as to allow the steam equal exit facilities on all sides of the cylinder C, and thereby treat all parts of the surrounding goods perfectly and equally. The cylinder

C is such as is ordinarily used for sponging goods, and this apparatus therefore combines the operations of sponging goods and mothproofing them at the same time.

20

Having described our invention, we claim—

The apparatus for treating and mothproofing goods, consisting of the concentric perforated cylinders A, B, and C, with their contained medicating-chamber D and mixing steam-chamber E, arranged and operated substantially as described.

25

W. H. GOODDAY.
LOUIS F. GEMEINER.
